UNITED STATES PATENT OFFICE.

WILLIAM LESLIE REID HALL, OF PEAK HILL, WESTERN AUSTRALIA,
AUSTRALIA.

GRIP DRIVING APPLIANCE.

SPECIFICATION forming part of Letters Patent No. 784,938, dated March 14, 1905.

Application filed April 6, 1904. Serial No. 201,934.

To all whom it may concern:

Be it known that I, WILLIAM LESLIE REID HALL, mine manager, a subject of the King of Great Britain and Ireland, residing at Peak Hill, in the British State of Western Australia, Commonwealth of Australia, have invented a new and useful Improved Grip Driving Appliance, of which the following is a specification.

This invention consists of an improved grip driving appliance for automatic ore-feeders of stamp-batteries and the like, the said appliance forming the medium for imparting an intermittent motion from the bumper-lever gear to the spindle which operates the feed-regulating gear of such as a "Challenge" or other ore-feeder.

The invention will now be fully described, aided by a reference to the attached sheet of drawings, in which—

Figure 1 is a side view showing the driving-grip in position upon its disk wheel, and Fig. 2 a plan of same, while Figs. 3 and 4 are plan and side views, respectively of the grip by itself, the latter view showing the opposite face of the grip to that shown in Fig. 1.

In said figures, A is the steel or other metal grip-lever, formed with jaws a' and a^2 on it, as shown; B, the metal rim disk fitted on end of the bevel-wheel spindle C in such as a Challenge ore-feeder; D, a link for connection to the spring E or other device which returns the grip to its normal free position. The grip-lever A has a hole A' in its outer end for connection with the lower end of a connecting-rod A ^{2} , the upper end of which is connected with the bumping-lever gear of the stamp-battery in the usual manner.

The wheel or disk B has a rim b' formed on it, the internal face of which receives the jaw a' of grip A, while the periphery of disk receives the jaw a^2 .

a^3 represents clearance-grooves, and a^4 an ear or projection on side of grip-lever to hold it in position upon the disk wheel B, while a^5 is a lug or projection on the top edge of grip-lever to retain the link D in position. By the said grip-lever being lifted at its outer end its jaws a' and a^2 grip the periphery and internal surface of the rim b' , and so rotate the disk B until the end of the upward stroke of the grip is reached, when the resilient action of the spring E upon link D draws the grip-lever downward, and at the same time freeing its grip-jaws from the rim of disk wheel and which latter will remain stationary until the next stroke of the grip-lever appliance takes place.

Having now described my invention, what I claim as new, and desire to secure by Letters Patent, is—

A grip-lever as A for the purpose specified provided with jaws a' and a^2 , clearance-grooves a^3 , ear a^4 and lug a^5 and with a hole as A' near its outer end substantially as described and shown.

In witness whereof I have hereunto set my hand, in the presence of two witnesses, this 15th day of February, 1904.

WILLIAM LESLIE REID HALL.
